DESIGN FOR A TINSEL ORNAMENT FOR CHRISTMAS TREES

Lambert L. Raymond, Minneapolis, Minn.

Application April 30, 1937, Serial No. 69,087

Term of patent 14 years

To all whom it may concern:

Be it known that I, Lambert L. Raymond, a citizen of the United States, residing at 2638 Upton Avenue, Minneapolis, in the county of Hennepin and State of Minnesota, have invented a new, original, and ornamental Design for a Tinsel Ornament for Christmas Trees, of which the following is a specification, reference being had to the accompanying drawing, forming part thereof.

Fig. 1 is a view in front elevation of the tinsel ornament showing my new design;

Fig. 2 is a view in side elevation thereof.

Fig. 3 is a partial view in front elevation of the ornament showing my design on an enlarged scale;

Fig. 4 is a horizontal section taken on line 4—4 of Fig. 3 as indicated by the arrows; and

Fig. 5 is a partial view in front elevation on a still more enlarged scale.

I claim:—

The ornamental design for a tinsel ornament for Christmas trees as shown.

LAMBERT L. RAYMOND.
